PHOTOGRAPHIC SLIDE EJECTOR-
RECEPTACLE

George J. Kollock, Atlanta, Ga.

Application August 31, 1950, Serial No. 182,456

3 Claims. (Cl. 312—55)

1

This invention relates to a storing and dispensing device, and more particularly, to a device for storing and dispensing photographic slides, pictures, cards and other substantially flat articles, and this application is a continuation-in-part of my co-pending application, Serial No. 48,436, filed September 9, 1948, entitled "Photographic, Slide Ejector-Receptacle."

It is desirable to store photographic slides and the like in such a manner as to maintain them free from dust or dirt, to have them conveniently accessible for use, to return them to their original container in chronological order, and to be able to do this in meager light or darkness without fumbling or getting finger prints on them. Accordingly, it is an object of my invention to provide a photographic slide dispensing device constructed to accomplish the desirable functions mentioned above.

Another object of the invention is to provide a device that is arranged and constructed to hold and protect photographic slides and the like and to dispense such articles conveniently, one at a time.

Another object of the invention is to provide a device of the character mentioned above that is simple and inexpensive to manufacture, rugged in construction, efficient in operation and compact in size so that it may be easily stored in an ordinary box, and readily assembled when desired.

Another object of the invention is to provide a device of the character mentioned above containing a storage box for photographic slides and the like which will contain these articles in a compact stack and which may be inserted easily, as a unit, within the dispensing device.

Another object of the invention is to provide a storing and dispensing device of the character mentioned above that may be simply adjusted to dispense photographic slides and the like of varying thicknesses.

Other and further objects and advantages of my invention will be apparent from the following description taken in connection with the accompanying drawing in which like characters of reference designate corresponding parts throughout the several views, and wherein:

Fig. 1 is a top plan view of a device constructed according to my invention.

Fig. 2 is a front elevation of the device in Fig. 1.

Fig. 3 is an isometric view of a detail.

Fig. 4 is an isometric view of a detail.

Fig. 5 is a cross-sectional view taken along line 5—5 in Fig. 2 and shows the operation of the dispenser.

2

In the embodiment chosen for illustration, an elongated and somewhat U-shaped frame is formed from sheet metal or other suitable material and consists of a flat rectangular area which forms back member 10, and a similar pair of opposed parallel side members 10' and 10'' which extend at right angles from the opposite edges of back member 10. Extending at right angles inwardly, along the upper and central outer edges of side members 10' and 10'' respectively, are retaining members 11 and 11'; and the bottom portions of members 10, 10' and 10'' respectively, are flanged out to form flange members 12, 12' and 12''. The frame thus described forms a rectangular hollow member which is open at its top, bottom and front portions and is clearly illustrated in Fig. 2.

Fig. 1 shows a base 13 which is also formed of sheet metal material and is rectangular in shape. Protruding from the center area of base 13 are raised flanged sections 14, 14' and 14'' which correspond with base flanges 12, 12' and 12'', respectively, so that these base flanges may slide under and be retained by the raised flanged sections. Felt pads 15 are fixed to the underside corner areas of base 13 to protect any surface upon which the base may be sitting. It is to be remembered that base 13 may easily be removed or slidably attached to the frame, so it may be stored separately when not in use.

Attached transversely in somewhat the mid-section of the frame is cross frame plate 16 which conforms to the inside cross-sectional shape of the frame. Flanges 17 and 17' (flange 17' being hidden in the drawing) are ears on the rearward corners of plate 16 which are bent downwardly to abut respectively sides 10' and 10''. Flanges 18 and 18' extend in a similar manner from the forward corners and abut the sides as described above. Flanges 17, 17', 18 and 18' are retained in place by rivets which pass through the respective sides and flanges and thus fix the position of plate 16 in the frame at a point slightly before the lower end of retaining members 11, 11'. Between the flanges 17, 17' and 18, 18' are opposed slides 19, 19' which are ears on plate 16 which are bent downwardly and inwardly to form channels beneath the plate to slidably retain finger plate 20. Finger plate 20 is a rectangular member which is slightly smaller in width than cross frame plate 16 so that it may slide thereunder. Fingers 21 and 21' are turned up at the rear of finger plate 20 and project through slots 22 and 22' respectively, formed in cross frame plate 16. A rectangular aperture is provided in

back member 10 to extend above and below cross frame plate 16 to allow the back member 10 to limit the backward motion of plate 20 and yet allow fingers 21 and 21' to pass therethrough. As shown in Fig. 5, the backward motion of finger plate 20 is limited by back member 10 and the forward motion is limited by the ends of slots 22 and 22'. Guides 23 and 23' are bent downwardly from the forward and center sections, respectively, of finger plate 20 and are parallel to back member 10 and spaced from each other.

A substantially L-shaped lever 24 is supported on braces 25 and 25' which are continuations of flanges 18 and 18' and the lever is pivotally retained in place by a rivet or other pivot pin. The uppermost end of this lever extends into the space provided between guides 23 and 23' to provide a camming action which actuates the traveling beam or finger plate 20. Fig. 5 illustrates the action of lever 24, with the broken lines showing its forwardmost position. Spring 26, which connects back member 10 with lever 24, pulls the lever to its rearward position as shown by the continuous lines. A push plate 27 mounted on the free end of lever 24 provides a convenient and easily accessible means for actuating the lever.

Fig. 3 illustrates a cartridge insert or feeder container 28 which is an elongated U-shaped member of rectangular cross-section corresponding in shape and length to the section of the frame member above plate 16, but slightly smaller so that it may be inserted therein. Detents 28' assure a snug sliding fit, and hole 28'' makes insertion and removal easy. Rolled edge shoulders 29 and 29' are provided along the bottom edges of the opposite sides of container 28 so that flat slides may be stacked thereon, as shown in Fig. 2 and Fig. 5.

The back of insert 28, adjacent shoulders 29 and 29' is cut away to provide proper clearance for fingers 21 and 21', and a bent bracket 33 is provided therebetween to assist the shoulders 29, 29' to retain the slides in place. A slideable clip 31, formed as shown in Fig. 3, is provided between the outer edges of container 28 and is detachably retained in place by friction. The body of clip 31 extends into container 28 to retain the slides in stacked position within the container.

A rectangular U-shaped cover 32, made of cardboard or the like is illustrated in Fig. 3 and may be placed over container 28 to provide a complete box for storage.

In the operation of the instant embodiment, the insert 28, with the slides in a stacked position and clip 31 removed, is inserted as shown in Fig. 2 so that shoulders 29 and 29' rest on cross frame plate 16 in such a way that slots 22 and 22' are aligned between shoulders 29 and 29'. When a slide is needed, push plate 27 is depressed moving finger plate 20 forward causing fingers 21 and 21' to push forward against the lowest slide forcing it out of front opening between the bottom of retaining members 11 and 11' and cross frame plate 16. When this projecting slide is removed and pressure is released from push plate 27, the next slide falls into position on the shoulders 29, 29'. Fig. 4 illustrates an adjuster plate 33 which may be installed between shoulders 29 and 29' and cross frame plate 16 to provide less clearance for the thinner slides. In this way, inserts holding slides of different thicknesses may be easily adjusted for.

Each container may be suitably labeled on cover 32 or elsewhere, so as to designate the container number, subject matter, etc., as desired.

Index tabs 34 may be placed on the slides to indicate different subjects or different sequences of the same subject.

By use of my invention, slides may be stored in the indexed containers until their use is desired, whereupon the cover is lifted from the container which is then placed in the frame member as described above. After use, each slide is returned in order to the open end of the device and dropped into the container so that the chronological order or sequence of slides is automatically maintained and thus the container is ready for immediate storing.

It will be obvious to those skilled in the art that various modifications and changes may be made in the device shown without departing from the scope of my invention as defined in the appended claims.

I claim:

1. In a device of the class described, a pair of side walls and a back wall connected together to form a channel shaped structure open at its top, a cross frame member extending from side to side between said side walls and arranged to divide said structure into upper and lower compartments, flanges projecting inwardly from said walls so as to partially close the front of said upper compartment, said flanges having ends positioned above said cross frame member, an open front container removably positioned in said upper compartment, said container engaging the side walls of said structure with a snug sliding fit, the open front of said container being adjacent to and accessible between said flanges on said side walls, said container having shoulders turned inwardly to support a stack of slides in said container, said container also having a supporting flange extending beneath said slides and terminating short of said shoulders to form a through slot between said supporting flange and each of said shoulders, slots in said cross frame member aligned respectively with each said through slot, a lever pivotally supported in said lower compartment, a traveling beam slidably mounted beneath said cross frame member and carrying fingers projecting respectively through each said through slot to bear against an edge of the bottom member of said stack of slides to eject said slides one at a time, driving guides depending from said beam, said lever having an end extending between said guides for camming action therewith to move said beam forward when said pivoted lever is depressed, and spring means connected to bias said lever to re-set it.

2. In a device of the class described, a pair of side walls and a back wall connected together to form a channel shaped structure open at its top, a base connected to said structure, a cross frame member extending from side to side between said side walls and arranged to divide said structure into upper and lower compartments, flanges projecting inwardly from said side walls so as to partially close the front of said upper compartment, said flanges having lower ends positioned above said cross frame member, an open front container removably positioned in said upper compartment, said container engaging the side walls of said structure with a snug sliding fit, the open front of said container being adjacent to and accessible between said flanges on said side walls, said container having shoulders turned inwardly to support a stack of slides in said container, said container also having a supporting flange arranged to extend beneath said slides and terminating short of said shoulders to

form a through slot between said supporting flange and each of said shoulders, slots in said cross frame member aligned respectively with each said through slot, flanges depending from said cross frame member and converging to form a support, a lever pivotally attached to said support, a traveling beam slidably mounted beneath said cross frame member and carrying fingers projecting respectively through each said through slot to bear against an edge of the bottom member of said stack of slides to eject said slides one at a time, driving guides depending from said beam, said lever having an end extending between said guides for camming action therewith to move said beam forward when said pivoted lever is depressed, and spring means connected to bias said lever to re-set it.

3. In a device of the class described, a pair of side walls and a back wall connected together to form a channel shaped structure open at both ends, a flanged base, flanges on said side walls and said back wall slidably connecting said structure to said base, a cross frame member extending from side to side between said side walls and arranged to divide said structure into upper and lower compartments, flanges projecting inwardly from said side walls so as to partially close the front of said upper compartment, said flanges having lower ends above said cross frame member, an adapter plate removably positioned on said cross frame member, an open front container removably positioned in said upper compartment, projections on said container engaging the side walls of said structure with a snug sliding fit, the open front of said container being adjacent to and accessible between said flanges on said side walls, said container having rolled edge shoulders

resting upon said adapter plate and turned inwardly to support a stack of slides in said container, said container also having a supporting flange extending beneath said slides and terminating short of said rolled edge shoulders to form a through slot between said supporting flange and each of said rolled edge shoulders, slots in said cross frame member aligned respectively with each said through slot, flanges depending from said cross frame member and converging to form a support, a lever pivotally attached to said support, a traveling beam slidably mounted beneath said cross frame member and carrying fingers projecting respectively through each said through slot to bear against an edge of the bottom member of said stack of slides to eject said slides one at a time, driving guides depending from said beam, said lever having an end extending between said guides for camming action therewith to move said beam forward when said pivoted lever is depressed, and spring means connected to bias said lever to re-set it.
